UNITED STATES PATENT OFFICE

170,393

AIRPLANE

Robert J. Woods, Grand Island, N. Y., assignor to
Bell Aircraft Corporation, Wheatfield, N. Y.

Application May 2, 1952, Serial No. 19,559

Term of patent 3½ years

(Cl. D71—1)

To all whom it may concern:

Be it known that I, Robert J. Woods, a citizen of the United States, residing at Oakfield Road, Grand Island, in the county of Erie and State of New York, have invented a new, original, and ornamental Design for an Airplane of which the following is a specification, reference being had to the accompanying drawing, forming part thereof.

Fig. 1 is a top plan view of an airplane, showing my new design;

Fig. 2 is a side elevational view thereof;

Fig. 3 is a front end elevational view thereof;
and

Fig. 4 is a rear end elevational view thereof.
I claim:

The ornamental design for an airplane, as shown.

ROBERT J. WOODS.
